CODE SENDER AND RECORDER

James C. Lewis, Olney Springs, Colo.

Application July 15, 1935, Serial No. 31,473

8 Claims. (CL. 35—14)

This invention relates to code sending and recording apparatus and has for an object to provide an insulated wire and electrical means under control of a telegraph key for scraping off the insulation in the form of dots and dashes whereby to effect the recording of a message.

A further object is to provide a switch contact having wiping contact with the indentations in the wire formed by the knife and an audible signal device in circuit with and controlled by the switch contact to reproduce the dots and dashes.

A further object is to provide code sending and recording apparatus which will be formed of a few, simple, durable and inexpensive parts which will be easy to manufacture and will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

25 In the accompanying drawings forming part of this specification,

Figure 1 is a side elevation of code sending and recording apparatus constructed in accordance with my invention.

30 Figure 2 is a plan view of the parts shown in Figure 1.

Figure 3 is an end elevation of the parts shown in Figure 2.

35 Figure 4 is an enlarged detail elevation showing the wire guide tubes, base shelf, and knife.

Figure 5 is a detail cross sectional view taken on the line 5—5 of Figure 1.

Figure 6 is a detail perspective view of the knife.

40 Figure 7 is a detail sectional view showing the switch contact in applied position for reproducing the dots and dashes.

Figure 8 is a detail elevation showing the switch contact in operative position on the wire.

45 Figure 9 is a diagrammatic view showing the wiring circuit for the knife and also the wiring circuit for the signal device.

50 Referring now to the drawings in which like characters of reference designate similar parts in the various views, the device is shown to comprise a base plate 10 from which rises a standard 11 having a shelf 12 projecting from the front face and braced by wings 13. The shelf forms a support for tubular wire guides 14 which are arranged in alignment and are spaced apart at the

inner ends. Rollers 15 are disposed at the ends of the support 12 and form antifriction bearings over which preferably enamel insulated wire 16 is fed through the tubular guides 14 from a supply spool 17 to a take-up spool 18, these spools being mounted on bearing arms 19 and 20 carried by the standard 11. The spools are interchangeably mounted on their shafts 21 and are held in place by thumb nuts 22 screwed on to the ends of the shaft in the usual manner.

5 By now referring to Figure 5 it will be seen that between the tubular guides 14 there is disposed an anvil 23 which is provided in the top face with a groove 24 to receive the insulated wire 16.

A knife blade 25 is disposed above the anvil and is provided midway between the ends with a curved sharp edge 26 which receives the wire when the knife descends and scrapes off the insulation from the wire as the wire passes along 20 the anvil from the supply spool to the take-up spool. The knife is provided with a U shaped arm 27 which embraces the shelf or support 12 and one leg of the arm is equipped with an armature 28 which is disposed below the support in 25 vertical alignment with the knife. The other leg of the arm is considerably thickened above the knife blade as shown at 29 in Figs. 5 and 6 and is provided with hinge ears 30 to receive the pivot pin 31 of an arm 32 which is pivotally connected 30 at the upper end to a spring arm 33 as shown at 34 in Fig. 5. The arm 33 is adjustably mounted upon a bracket arm 35 carried by the shelf or support 12. The knife is thus hung or suspended over the anvil by the spring arm 33 which normally holds the knife blade raised or in released position. The spring arm 33 is adjustably confined in a slotted enlargement 36 in the upright arm 35, by means of a set screw 37.

Underneath the shelf or support 12 an electro- 40 magnet 38 is secured to the standard 11 by means of a bracket 39. The core 40 of the electromagnet is disposed in vertical alignment with the armature 28 and when the electromagnet is energized the armature is attracted and moves the 45 knife downwardly to intercept the insulated wire during its travel along the anvil and scrape the insulation from the wire. When the electromagnet is deenergized the spring arm 33 moves the knife out of contact with the wire into raised or 50 released position. The terminal wires 41 of the electromagnet are led to a socket 42 carried by an insulating base 43 mounted on the base plate 10.

55 The terminal wires 41 from a telegraph key

45 and battery 46 may be plugged into the socket 42 as shown diagrammatically in Figure 9 so that when the key is depressed the knife will be held in contact with the traveling insulated wire 16, and when the key is released the electromagnet will be deenergized and release the knife. The dots and dashes thus made by the key will be recorded on the wire 16 in the form of indentations exposing the bare wire and elevations consisting of undisturbed insulation as best shown in Figure 8.

To reproduce the code message the prepared wire carrying the code message may be again passed along the anvil in the same direction as during the insulation scraping operation. A substantially triangular switch contact 47 is now substituted for the knife 29 by removing the pivot pin 31 to disengage the arm 27 from the arm 32, and the pivot pin may now be passed through 20 the hinge eyes 49 which are on the switch contact 47 to secure the contact to the arm 32. A flexible wire 50 is connected at one end as shown at 51 to the spring arm 33 and the opposite end is equipped with a plug 52 which may be plugged 25 into a socket 53 in the insulating base 48 to connect the contact in circuit with a buzzer 53 or other audible signal device as shown diagrammatically in Figure 9. The switch contact 47 is spring pressed by the arm 33 to have wiping 30 contact with the wire 16 as shown in Figure 8 and during travel of the wire the guide tubes orient the wire to dispose the indentations underneath the contact so that the indentations, corresponding to the dots and dashes, will operate the 35 buzzer 53 to reproduce the code message.

A motor 54 is mounted on the base plate 10 and the pulley 55 of the motor is connected by a belt 56 to a pulley 57 on the shaft 21 of the take-up spool 18. The motor may be wired to 40 a socket 58 on the insulating base so that a flexible cable or cord from the house circuit may be plugged in to operate the motor. A brake 59, as best shown in Figure 1, is mounted on the base plate 10 and frictionally engages the rim of the 45 supply spool 17 to retard the speed of this spool while the wire 16 is being unwound therefrom so that the wire will be held taut at all times during travel over the anvil 23.

From the above description it is thought that 50 the construction and operation of my invention will be fully understood without further explanation.

What is claimed is:

1. In code sending and recording apparatus, an insulated wire, an electrically operated knife for scraping the insulation off the wire in the form of dots and dashes, a telegraph key in circuit with and controlling the knife, and spools for feeding the wire past the knife.
2. In code sending and recording apparatus, an insulated wire, supply and take-up spools for the wire, a knife movable to intercept the wire

between the spools and scrape the insulation off the wire in the form of dots and dashes, an electromagnet for moving the knife in one direction, a spring for moving the knife in the opposite direction, and a telegraph key in circuit with and controlling the electromagnet.

3. In code sending and recording apparatus, an insulated wire, supply and take-up spools for the wire, a knife movable to intercept the wire between the spools and scrape the insulation off the wire in the form of dots and dashes, a support for the wire underneath the knife, a curved arm carried by the knife and embracing the support, an armature on the arm beneath the support, an electromagnet associated with the armature for moving the knife in one direction, spring means mounting the knife above the support and moving the knife in the opposite direction, and a telegraph key in circuit with and controlling the electromagnet.

4. In code sending and recording apparatus, an insulated wire, supply and take-up spools for the wire, a support, guide tubes on the support disposed in alignment and spaced apart at the inner ends, a knife movable to intercept the wire between the guide tubes and scrape the insulation off the wire in the form of dots and dashes, an arm integral with the knife, a spring arm pivoted to the knife arm and holding the knife normally in released position, a U-shaped arm embracing the support and having one leg secured to the knife, an armature on the other leg disposed below the support in alignment with the knife, an electromagnet associated with the armature for moving the knife to engage the wire, and a telegraph key in circuit with and controlling the electromagnet.

5. In code sending and recording apparatus, enamel insulated wire having uninsulated portions forming telegraphic code signals, a switch contact spring pressed to have wiping contact with said wire, means for feeding said wire past the contact, and an audible signal device in circuit with and controlled by the contact.

6. In code sending and recording apparatus, an enamel insulated wire having uninsulated portions forming telegraphic code signals, wind off and take up spools for feeding the wire, a pointed switch contact having wiping contact with the wire, and an audible signal device in circuit with and controlled by the contact to reproduce the dots and dashes.

7. A wire insulated with enamel and having recorded telegraphic code signals consisting of uninsulated portions of the wire.

8. In apparatus of the class described, an enamel insulated wire having uninsulated portions forming telegraphic code signals, means for sending an electric current through the wire, and means for closing an electric circuit at uninsulated portions of the wire.

JAMES C. LEWIS.
